Charles L. Stokes

UNITED STATES PATENT OFFICE

CHARLES LAWRENCE STOKES, OF LOS ANGELES, CALIFORNIA

INTERNAL-COMBUSTION ENGINE

Application filed August 22, 1924. Serial No. 733,573.

My invention relates to improvements in the construction of internal combustion engines and is particularly applicable to the construction of two-cycle engines.

The principal object of my invention is to provide improved means for the operation of the engine described in my Patent No. 1,308,560, July 1st, 1919, and has particular reference to the structure shown in Fig. 4 thereof.

With our present day motor fuels it is highly desirable to prevent the leakage of gasoline past the piston ring into the crank case, in order to avoid dilution of the lubricating oil in the crank case. In my present invention I am enabled to do this by the structure to be defined by reason of the efficient vaporization of the liquid fuel prior to its entry into the compression chamber of said engine and further I provide means for maintaining unvaporized liquid fuel separate from said compression chamber so that the same may be injected into the combustion chamber of said engine for its efficient utilization.

Referring to the drawings, in which the same numbers indicate like parts:

Fig. 1 is a vertical sectional view of my improved engine.

Fig. 2 is a side view in elevation of Fig. 1.

As described in my aforesaid patent, my engine structure essentially includes a water jacketed cylinder 1, the lower part of which forms the upper half of a crank case, the lower part of the crank case 2 being suitably bolted to the upper part in any well known manner. Within the cylinder is arranged a piston sleeve valve 3 for reciprocation therein, the lower part 4 of which being adapted to reciprocate in an enlarged portion of the cylinder wall.

A piston 5 is arranged to reciprocate within the sleeve valve 3 and a connecting rod 6 imparts the motion of piston 5 to a crank pin 7 forming part of the crank shaft 8. On either side of the crank pin 7 on the crank shaft 8 is arranged an eccentric 9 on which is mounted connecting rods 10 joined to 3 and 4 for the reciprocation thereof in substantially opposed phase to the piston 5. If

desired a counter weight 11 may be placed on the crank shaft, especially if the engine is built in multi-cylinder form, but the same is not necessary for the operation of the engine.

In the water jacket surrounding the cylinder bore are passages 12 and 13, which passages are cored out in the casting to form passages for the inlet and egress of combustible mixture from the compression chamber 14 to the combustion chamber 15.

The inlet of combustible mixture from the carburetor 16 to 13 is controlled by the action of a rotary valve 17, driven at engine speed from the front end of the crank shaft 8 by a chain 18 and the inlet of combustible mixture from 12 to 15 is controlled by the sleeve valve 3 which has an upper belt of inlet ports 19 and a lower belt of inlet ports 20 which are arranged to co-act at predetermined periods with passages 21 and 22 respectively in the cylinder casting. A belt of the exhaust ports 23 is arranged concentrically in 3 to co-act at predetermined periods with an exhaust passage 24 arranged in the cylinder casting and 24 is preferably arranged substantially centrally of 21 and 22. The outer end of the cylinder bore is closed by a water jacketed cylinder head 25 of any well known and suitable construction. The rotary valve 17 is arranged to open on to a deflector 26 arranged to pass liquid fuel on the exterior of the heated cylinder wall within the passage 13.

The operation of my construction is generally understood by reference to my aforesaid patent, but in the present instance I provide that in the operation of my engine improved results are now obtained. If it is assumed that the piston 5 is on its outer, or compression, stroke, the ports 19, 20 and 23 will be shrouded by the cylinder wall due to the inward or suction stroke of the sleeve valve 3. At the same time the rotary valve 17 is timed to open thereby supplying a combustible mixture from the carburetor 16 responsive to the suction generated by 4, and this flow of combustible mixture will be allowed to continue substantially until 4 has

reached the innermost limit of travel when 17 will be arranged to close.

A power impulse is then imparted to 5 whereupon 5 will move to its innermost position of travel and 4 will move to its outermost limit of travel thus compressing the combustible charge in 14 which is contained in 12 for passage through 20 and 21 for scavenging the exhaust gases through 24. Such exhaust 10 gases pass to atmosphere through the exhaust port 27 thereby heating the metal separating 27 from 13 and thus forming a so-called "hot spot" for the vaporization of fuel drawn into 13.

15 The mixture of liquid fuel and air supplied to any well known carburetor 16 generally resolves itself into liquid vaporized fuel and unvaporized liquid fuel. The unvaporized liquid fuel is deflected by 26 to the exterior 20 wall of the cylinder being retained thereon for a greater or less length of time while moving in a downward direction towards 14. The retention of this liquid fuel is arranged 25 so that the time element is sufficient for its contact and vaporization by the "hot spot" 27 to the end that only vaporized fuel is drawn into 14 for forcing through 12 into 15.

This is highly advantageous in two-cycle 30 operation and further by now providing a mechanically operated valve 17, I am enabled to offer increased volumetric efficiency for two-cycle engines by providing a clear passage from the carburetor to the compression chamber and from the compression chamber to the combustion chamber without the use of any auxiliary, or automatic, valves.

Thus in my former patent, automatic valves 40 were provided for the ports 28 and 29 but I am now enabled to dispense with the use of such valves. If desired the passage 12 may be dispensed with by closing the port 29 and making the passage 12 a part of the water jacket, in which case the passages 21 and 22 would also be closed off from 12 but would 45 open into 13. In certain designs embodying my invention this may be desirable for the utilization of certain kinds of fuel whereby the fluctuation of combustible mixture in 13 would tend to retain all liquid fuel in 13 until 50 discharged in a vaporized, or liquid, condition into 15; but all such modifications are apparent to those skilled in the art.

55 Valve 17 may be one of a number of well known constructions for effectively distributing a combustible mixture and it is to be noted that the same is never at any time subject to explosion pressure, but has only to retain the compression pressure in 13. Owing to this fact, 17 may be of simple structure 60 to cause no warping of the same can ever take place and consequently the manifold 30, containing valve 17, may be easily arranged for multi-cylinder engines of this type.

I claim:

65 1. An internal combustion engine compris-

ing a cylinder constituting a fuel explosion chamber, a piston reciprocating therein and a sleeve valve encircling the piston, said sleeve valve and cylinder having co-ordinating belts of ports, means for supplying gaseous fuel under pressure through said ports to the cylinder and means for supplying liquid fuel and air to said first mentioned means; said liquid fuel and air supplying means including a passage formed on one side by the exterior wall 70 of the cylinder wherein the liquid fuel is converted into gaseous fuel prior to its initial compression.

2. An internal combustion engine comprising a casing, a cylinder in said casing, said cylinder constituting an explosion chamber, a piston reciprocating therein and a sleeve valve encircling the piston, said sleeve valve and cylinder having co-ordinating belts of ports, means for supplying gaseous fuel under pressure through said ports to the cylinder and means for supplying liquid fuel and air to said first mentioned means; said liquid fuel and air supplying means including a passage 80 in said casing heated by exhaust heat from the cylinder, a carburetor for liquid fuel and air and a valve controlling the entry of liquid fuel and air to the passage wherein the liquid fuel is converted into gaseous fuel prior to its initial compression.

95 3. An internal combustion engine comprising a cylinder and a fuel passage contiguous to said cylinder, a piston reciprocating therein and a sleeve valve encircling the piston, said sleeve valve and cylinder having co-ordinating belts of ports, means including a compression chamber in permanent communication with said passage for supplying gaseous fuel under pressure through said ports to the cylinder and means for supplying liquid 100 fuel and air to said first mentioned means; said liquid fuel and air supplying means including a passage heated by exhaust heat from the cylinder and by the wall of said cylinder, a carburetor for liquid fuel and air and a rotary valve controlling the entry of liquid fuel and air to said last named passage wherein the liquid fuel is converted into gaseous fuel prior to its initial compression.

115 4. In a two-cycle internal combustion engine, a cylinder, a piston reciprocating therein and a sleeve valve encircling the piston, said sleeve valve and cylinder having co-ordinating belts of ports, means for supplying gaseous fuel under pressure through said 120 ports to the cylinder and means for supplying liquid fuel and air to said first mentioned means; said liquid fuel and air supplying means including a passage extending longitudinally of, and having a wall in common with, the exterior wall of the cylinder, a carburetor for liquid fuel and air, and means for deflecting the liquid fuel from the carburetor on to said common wall as the same 125 enters said engine.

130

5. In an internal combustion engine, the combination with a cylinder having a water jacket and a lateral port, of a sleeve valve controlling said port for introducing an explosive fluid to the cylinder, a compression chamber below said cylinder, a passage longitudinally through the water jacket for conducting the said fluid to said compression chamber, and means for vaporizing part of said fluid in the passage.

10 6. In an internal combustion engine of the two cycle type, a cylinder, a compression chamber, an intake passage in permanent connection with said chamber, a piston reciprocating in said cylinder, a sleeve valve for admitting an explosive mixture from said compression chamber to each end of said cylinder through said intake, an exhaust port midway between the ends of said cylinder, an intake 15 passage surrounding said exhaust, and a valve for admitting an explosive mixture to said compression chamber.

20 7. In an internal combustion engine of the two cycle type, a cylinder, a compression chamber, an intake passage in permanent communication with said chamber, a piston in said cylinder, a sleeve valve for controlling the admission of an explosive mixture from said chamber to said cylinder through said 25 intake passage and for permitting the escape of exhaust gases therefrom, a rotary valve for controlling only the admission of an explosive mixture to said chamber, and means for rotating said valve.

30 8. In an internal combustion engine, a cylinder, a piston, means for reciprocating said piston within said cylinder, a water jacket for said cylinder, an exhaust and an intake passage for said cylinder, said intake passage 35 surrounding said exhaust passage within said jacket, and means operating in timed relation to the operation of said piston for controlling the passage of the intake and exhaust gases through said passages.

40 45 Signed at Wilmington, in the county of Los Angeles and State of California, this 18th day of July A. D. 1924.

CHARLES LAWRENCE STOKES.
